Primary Examiner — Susan Bennett Hattan*Assistant Examiner* — Marie D. Fast Horse(74) *Attorney, Agent, or Firm* — Sheridan Ross P.C.(57) **CLAIM**

The ornamental design for a vehicle wheel, as shown and described.

DESCRIPTION

FIG. 1 is a front view of a vehicle wheel showing my new design;

FIG. 2 is a front perspective view thereof; and,

FIG. 3 is a rear view thereof.

The broken lines show portions of the vehicle wheel which form no part of the claimed design.
